UNITED STATES PATENT OFFICE.

FELIX E. DUNN AND JULIUS E. PATTERSON, OF KLAMATH FALLS, OREGON.

LAND LEVELER AND GRADER.

Application filed April 16, 1923. Serial No. 632,225.

To all whom it may concern:

Be it known that we, FELIX E. DUNN and JULIUS E. PATTERSON, citizens of the United States, residing at Klamath Falls, in the county of Klamath, State of Oregon, have invented new and useful Improvements in Land Levelers and Graders, of which the following is a specification.

This invention relates to improvements in apparatus for leveling and grading industrial and agricultural land, roadways, and the like and resides in the provision of apparatus by means of which such operations may be more economically, effectively and expeditiously carried out.

An object of the invention is to provide vehicular apparatus of the character described which during the continuous progress thereof and at the will of the operator, by manipulation of a single control element, the apparatus may be caused to pick up or scoop, to convey and to dump dirt or other material.

Another object of the invention is to provide apparatus of the character described wherein the scoop, forming a part of the invention may be, at will, moved into and maintained in any one of its various positions by an easy manipulation of a single control element during and without interrupting the progress of the vehicle forming a part of the apparatus.

A further object is to provide in apparatus of the character described means with which the depth of the scooping action may be regulated as desired and the dumping operation may likewise be regulated so that either a gradual dumping or quick dumping action may be effected.

Another object is to generally improve and simplify the construction and operation, reduce the cost of manufacture and render more generally useful grading and leveling apparatus of the type described.

Another object is to provide apparatus of the character described in which the parts and elements of the apparatus will be automatically returned to normal position.

Another object is to provide in apparatus of the character described automatic and semi-automatic control and operating mechanism which will facilitate the work of scooping, conveying and dumping dirt or other material particularly in that it will simplify and render more efficacious the operation of the apparatus.

A further object is to provide an apparatus of the character described in which the scoop when empty and upon manipulation of the operating member, will move into scooping position but when loaded and in load conveying position, upon again operating in the same manner, the same operating member will move into dumping instead of scooping position, this being automatically provided for through the operation of release mechanism by engagement of the dirt in the scoop with a trip member forming part of the last named mechanism. These operations with others described, work to the advantage of making it unnecessary for the operator to frequently turn or look behind during the operation of the apparatus.

A further object is to provide in apparatus of the character described, a wheeled support for the scoop in which the axle is constructed whereby it will act as a lever to impart the necessary force to the mechanism to operate the scoop, thus doing away with gears, and other parts and simplifying and reducing the cost of the apparatus.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 represents a side elevation partly in section of the apparatus of our invention showing the scoop in inoperative position as when empty, this position being substantially the same as load conveying position, which latter is made out in dotted lines.

Fig. 2 represents a top plan view of the apparatus of our invention.

Fig. 3 is a sectional view showing in elevation the main elements of the mechanism and the scoop in scooping position.

Fig. 4 is a view similar to Fig. 3 showing the mechanism in dumping position.

Referring to the embodiment of the invention shown in the accompanying drawings, it will be seen that the vehicular part of the construction of the apparatus comprises an axle 1, provided with off set spindles 2 sup-

porting wheels 3. A tongue or draw bar 4 is attached to rearwardly extending bars 5, which bars at their rear ends are pivoted as at 6 to plates 7 bolted to the substantially upright portions 8 of the axle 1. The plate 7 is secured to the axle so that it projects forwardly therefrom and in its forwardly projecting portion the pivot 6 is carried.

Connected to the pivot 6 and depending therefrom are hangers 9 which are secured as at 10 to the sides of a scoop 11, near the forward end of the scoop. Upon forward movement of the axle, the scoop will lower and on the opposite movement of the axle 15 the scoop will be lifted. Through this connection, a leverage action is provided upon movement of the axle which, in combination with other mechanisms to be described, will provide for the movement of the scoop into 20 its several positions.

The wheels 3 are loosely mounted on the axle but are adapted to be locked thereto by clutch mechanisms 12. The clutch mechanisms are of simple construction, one of the 25 same being illustrated in detail in Fig. 1. Each comprises an inner drum 13 fixed to the spindle of the axle and the outer drum 14 fixed to the hub of the wheel. Ordinarily these drums move relative to one another. 30 The inner drum carries a split band 15 which is arranged to expand and contract by mechanism consisting of a retractile spring 16 fastened to the inner drum at one end as at 17, and at its other end to the inwardly off-set end 18 of the band 15. Pivoted on the inner drum as at 19 is an eccentric sheave 20 to which a flexible operating element 21 is fastened. The sheave is provided with an abutment or projection 22 at one side of its 40 pivot member 19, which pivot member is adapted to bear against the off-set end 18 and move said end so as to expand the ring 15 when the sheave is moved in a counter-clockwise direction. This expansion of the band 45 is against the action of the spring, which spring normally holds the band in contracted position permitting relative movement of the drums. The flexible element 21 is connected with a pedal 23 suitably supported by 50 the tongue or draw bar structure adjacent the operator's seat, not shown, it being understood that the ordinary agricultural implement seat may be provided on the apparatus as is customary.

55 By depressing the pedal 23, the flexible element wound on the sheaves will be pulled and cause the sheaves to turn and expand the inner drums of the clutches. This will cause the wheels to lock so that upon turning 60 thereof, the axle will be turned likewise. Since the axle is off-set, it will swing forwardly and downwardly from its normal position shown in Fig. 1, and in so doing effect a leverage action, as will be later more fully described, and operate the scoop. The clutch

is progressive and requires continued movement or depression of the pedal in order to move the scoop from normal position into scooping position. If the pedal is depressed but slightly and held in this position, the 70 scoop will move downwardly but to a slight extent and remain in such position. By this arrangement it will be seen that the depth at which the scoop will operate may be regulated.

As a means for automatically lifting the scoop into load conveying position following its being loaded during a scooping operation, we provide cylinders 26 which are pivoted to a bar 27 extending transversely between 80 and secured to the plates 7. In these cylinders are mounted rods 28 the inner ends of which carry members 29 similar to pistons, the outer ends of which are pivoted to brackets 30, which are supported by the 85 scoop. Helical expansion springs 31 are mounted in the cylinders and their forward ends are adapted to be engaged by the members 29 while their rear ends engage the flanged caps 32 which are screwed onto the 90 rear ends of the cylinders. The other ends of the cylinders are closed by similar caps 33. Since the cylinders are carried by the plates which are attached to the axle, when the axle and plates move forwardly, the cylinders are likewise moved relative to the rods 29 and cause the springs to compress, said springs being therefore under compression when the scoop is moved into scooping position. Upon release of the scoop mechanism 12, the springs will expand and cause the axle and its associated parts to return to 95 normal position and thereby lift the loaded scoop into position clear of the ground substantially as shown in Fig. 1. The springs are sufficiently stiff to lift the loaded scoop.

As a means for controlling the movements of the scoop, we provide mechanism as follows: Attached to a shaft 34 journaled between the bars 5 and extending downwardly and rearwardly from the bar, are hooks 35, the hook or bill portions 36 of which are adapted to cooperate with projections 37 extending outwardly from the sides of the scoop. The projections 37 are preferably provided with right angularly bent terminals 38 which serve as keepers to hold the hooks against lateral displacement. Normally, that is when the scoop is in empty and "up" position, the bolts or hook portions 36 are disposed below the projections 37 and this permits the scoop to turn on its axis so as to bring its forward or scooping edge into a plane lower than the rear edge and to maintain this position while the scoop is lowering. As soon as the portions 36 engage the members 37, the scoop is prevented from turning on its axis, the pivot 6, and is moved bodily downwardly into scooping position.

Fixed to the bar 34 centrally of the ends thereof, is a leaf spring trip member 39 which curves downwardly and rearwardly to a point spaced above the bottom of the scoop. As the dirt accumulates in the scoop, it will push upwardly on the spring trip 39, and place said trip under tension. The tension of the spring has no effect on the bar 34 and hooks 35 at this time because of the engagement of the bills 36 with the projections 37. However, when the operator releases the clutch after a scooping operation and the scoop has become filled or loaded, the springs 31 quickly move the scoop into load conveying position, clear of the ground, and this movement causes the portions 37 to be disengaged from the hooks. Coincident to this disengagement, the stored up energy of the spring 39 is expended and causes the bar 34 to rotate and lift the hooks into a position whereby upon again operating the mechanism and the scoop moves downwardly, the portions 37 move clear of the hooks, and the scoop will turn on its axis and dump the load.

The hook members 35 are limited in their upward movement by the stop members 40 with which latter they engage when the spring trip 39 exerts a force to lift said hook members. The upward movement of the scoop is limited by stop members 41 which extend upwardly from the sides of the scoop at the forward end thereof and are adapted to engage the under sides of the bars 5. As a safety element to prevent movement of the scoop downwardly beyond a predetermined position, there are provided stop pins 42 on the plates 7, which pins are adapted to engage the upper edges of the bars 5 as shown in Fig. 3.

Assuming that the device is in the position shown in full lines in Fig. 1 and is ready to be operated, the operator depresses the pedal 23 and pulls on the flexible elements 21 so that the sheaves 20 are turned on their pivots 19. This moves the pins 22 so that they press outwardly on the portions 18 of the expandable hands 15 and cause the latter to expand and to frictionally lock with the outer drums 14. Through this action of the clutches the wheels are locked with the spindles of the axle and the axle is caused to turn. In order to continue the movement of the axle, the operator must continually press downwardly on the pedal as the vehicle advances. The turning of the axle causes the off set portion of the axle to swing forwardly and downwardly in an arc, producing a leverage action which through the hanger members 9 causes the scoop to lower. When the scoop first lowers it swings on the axis 6 so that the forward edge is swung downward and rearward in an arc and assumes a position below the rear edge of the scoop whereby the entire scoop is inclined forwardly and downwardly in proper scooping position. This swinging movement of the scoop is limited and ceases when the projections 37 engage in the hook portions 36 and from then on the movement of the scoop is a bodily one and downward. As the scoop moves bodily downward, the springs 31 are compressed but the tendency of the springs to lift upwardly on the rear end of the scoop is overcome by engagement with the hook portions 36 with the projections 37. The operator must maintain the pedal 23 depressed while the scooping operation is being effected, the parts being then in position shown in Fig. 3 of the drawing. As soon as the scoop is loaded and the operator desiring to lift the scoop from the ground in order that the load may be conveyed, releases the pedal 23. This releases the clutches and the springs 31 act to lift upwardly on the rear portion of the scoop and to cause the off set portion of the axle to swing upwardly and rearwardly. The upward and rearward swinging of the axle, through the hanger members 9, lifts upwardly on the front portion of the scoop and this action on the front and rear portions of the scoop, causes the scoop to be lifted clear of the ground in substantially level position. During the scooping operation, as soon as the dirt begins to accumulate in the scoop, it presses on the trip 39 and places same under tension. When the clutch is released as previously described, the projections 37 move clear of the hook portions 36 when the scoop is raised, and the springs 39 immediately expand and cause the hooks 36 to be lifted into dotted line position shown in Fig. 1, clear of the said projections. When it is desired to dump the load, the operator again presses the pedal 23 and the clutches again lock the wheels with the axle so that the axle swings forwardly as though to lower the pan, as in the initial operation. However, since the dirt is holding the spring trip 39 in such position that it exerts a force on the hook members sufficient to hold them in inoperative position, as the axle moves forwardly it tends to swing the forward edge of the scoop downwardly and rearwardly, that is, to turn the scoop bodily into downwardly and forwardly inclined position. Ordinarily the hooks 36 would prevent this motion but since the hooks are held clear of the members 37, the scoop is unobstructed and may be tilted into an inclined position to dump the load. By varying the movement of the pedal 23, the inclined position into which the scoop will be moved, may be varied. If it is desired to gradually unload so as to scatter the load, the scoop is moved into but a slightly inclined position and maintained in this position while the apparatus is being drawn forwardly. If it is desired to dump the

load, the operator releases the pedal 23 and the clutches again lock the wheels with the axle so that the axle swings forwardly as though to lower the pan, as in the initial operation. However, since the dirt is holding the spring trip 39 in such position that it exerts a force on the hook members sufficient to hold them in inoperative position, as the axle moves forwardly it tends to swing the forward edge of the scoop downwardly and rearwardly, that is, to turn the scoop bodily into downwardly and forwardly inclined position. Ordinarily the hooks 36 would prevent this motion but since the hooks are held clear of the members 37, the scoop is unobstructed and may be tilted into an inclined position to dump the load. By varying the movement of the pedal 23, the inclined position into which the scoop will be moved, may be varied. If it is desired to gradually unload so as to scatter the load, the scoop is moved into but a slightly inclined position and maintained in this position while the apparatus is being drawn forwardly. If it is desired to dump the

load quickly so as to form a pile, the pedal is depressed to its fullest extent and the scoop will quickly swing into substantially upright position as shown in Fig. 4.

5. To return the scoop and associated parts to normal position, the pedal is released following the dumping operation and the scoop will swing back into normal position as shown in Fig. 1.

10. With the improved grading device of our invention, it will be seen that the operator may efficaciously operate the grader to scoop, convey and dump the load, through manipulation of a single operating element.

15. Not only does the single operating element provide for setting into operation the mechanism of the apparatus but for the control of movement of the scoop as to the depth at which it is to operate and as to the manner in which it is caused to dump the load, either abruptly or gradually. With the apparatus of this invention, gears, rack bars and other expensive and space consuming parts, such as are usually employed in automatic scrapers, are dispensed with and not only is the apparatus simplified as to construction but it is materially reduced as to cost.

It will be seen that the axle virtually 30 provides a crank arm in its off set construction, which crank arm simplifies the construction, arrangement and operation as opposed to other motion transmitting arrangements, particularly because it does not 35 produce as much friction or wear out as quickly, nor is as much care and attention required to maintain the same in working form.

We claim:

40. 1. Land leveling and grading apparatus comprising an axle having a crank portion, wheels mounted for free rotation on extremities of the axle, a draw bar, means for pivotally connecting the draw bar with the 45 crank portion of the axle, clutch means associated with the wheels and axle for locking the wheels to and causing movement of the axle upon movement of the wheels, a scoop, members rigidly connected with the scoop 50 and pivotally connected with the crank portion of the axle and spring devices connected with the crank portion of the axle and with the rear portion of the scoop, which spring devices are placed under tension when the 55 scoop is moved into and maintained in scooping position.

2. Land leveling and grading apparatus comprising an axle having a crank portion, wheels mounted on the extremities of the 60 axle for free rotation thereon, a draw bar pivotally connected with the crank portion of the axle, a scoop, clutch means for locking the wheels to the axle to cause movement of the axle upon movement of the 65 wheels, means including the clutch means

which, when the axle is moved will move the scoop into scooping and dumping positions and spring means associated with the mechanism so as to be placed under compression when the scoop is in scooping position and will cause it to move the scoop into load conveying position upon declutching of the clutch mechanism.

3. Land leveling and grading apparatus comprising an axle, wheels mounted on the 75 axle, a scoop, a draw bar associated with the axle, means including clutch mechanisms for locking the wheels with the axle and moving the scoop into and maintaining the same in scooping position and means acting 80 automatically upon declutching of the clutch mechanisms for moving the scoop into load conveying position.

4. Land leveling and grading apparatus comprising an axle, wheels mounted on the 85 axle, a scoop, a draw bar associated with the axle, means including clutch mechanisms for locking the wheels with the axle and moving the scoop into and maintaining the same in scooping position, means acting 90 automatically upon declutching of the clutch mechanisms for moving the scoop into load conveying position and means which when the clutch mechanisms are operated following movement of the scoop into load 95 conveying position will cause the scoop to move into load dumping position.

5. Land leveling and grading apparatus comprising an axle, wheels loosely mounted on the axle, a scoop, a draw bar associated with the axle, means including clutch mechanisms for locking the wheels to the axle to cause rotation of the latter, which means operates to move the scoop into an operative position upon such movement of the axle, 100 means acting when the scoop is empty and is moved into said operative position to prevent tilting of the scoop, means operating on release of the clutch mechanisms to move the scoop into position clear of the ground 110 and means actuated automatically by the dirt in the scoop to release said tilt preventing means and permitting the scoop to tilt and dump the load upon second operation of the clutch mechanisms.

6. Land leveling and grading apparatus comprising an axle, wheels rotatable on the axle, a scoop, a draw bar associated with the axle, means associated with the axle and the scoop for moving the scoop into scooping position, clutch means associated with the wheels and upon the actuation of which causes the last named means to move into and maintain the same in scooping position, and spring means which when the clutch mechanisms are released following a scooping operation will automatically lift the scoop into load conveying position.

7. Land leveling and grading apparatus comprising an axle, wheels rotatable on the 130

- axle, a scoop, a draw bar associated with the axle, means associated with the axle and the scoop for moving the scoop into scooping position, clutch means associated with the 5 wheels and upon the actuation of which causes the last named means to move into and maintain the same in scooping position, spring means which when the clutch mechanisms are released following a scooping operation will automatically lift the scoop into load conveying position and means operated automatically by the dirt in the scoop, which when the clutch mechanisms are operated following movement of the scoop into load 10 conveying position will permit the scoop to tilt and dump the load.
8. Land leveling and grading apparatus comprising an axle having a crank portion intermediate of its ends, wheels rotatable on 20 the extremities of the axle, clutch mechanisms for locking the wheels to the axle and causing movement of the crank portion, a scoop, a draw bar associated with the axle, members rigidly connected with the scoop 25 adjacent the forward end thereof and pivotally connected with the crank portion, spring means connected with the crank portion and with the rear portion of the scoop and normally maintaining the scoop in lifted position clear of the ground.
9. Land leveling and grading apparatus comprising an axle having a crank portion intermediate of its ends, wheels rotatable on the extremities of the axle, clutch mechanisms for locking the wheels to the axle and causing movement of the crank portion, a scoop, a draw bar associated with the axle, members rigidly connected with the scoop 30 adjacent the forward end thereof and pivotally connected with the crank portion, spring means connected with the crank portion and with the rear portion of the scoop and normally maintaining the scoop in lifted position clear of the ground.
10. Land leveling and grading apparatus comprising an axle having a crank portion 55 intermediate of its ends, wheels loosely mounted on the extremities of the axle, a scoop, arms connected with the scoop near the forward end thereof and pivotally connected with the crank portions, spring devices connected with the crank portions and with the rear portion of the scoop, which spring devices normally maintain the scoop in lifted position and are placed under compression when the scoop is moved into scooping position, clutch mechanisms for locking the wheels to the axle and causing swinging of the crank portion, means for preventing the scoop from tilting upon swinging of the crank portion to move the scoop into scooping position and means for releasing said last named means operated automatically by the dirt picked up in the scoop.

JULIUS E. PATTERSON.
